US0D1030741S

(12) **United States Design Patent** (10) **Patent No.:** **US D1,030,741 S**
(45) **Date of Patent:** **** Jun. 11, 2024**

(54) **SET OF ELECTRONIC DEVICES**

(71) Applicant: **SpotOn Transact, LLC**, San Francisco, CA (US)

(72) Inventors: **Carol Marie Oles**, Baldwin, MD (US); **Doron Friedman**, Glenco, IL (US); **Jeffrey Haller**, Redwood City, CA (US); **Zachary Alan Hyman**, Belvedere, CA (US); **Kenneth John North**, San Carlos, CA (US)

(73) Assignee: **SpotOn Transact, LLC**, San Francisco, CA (US)

(**) Term: **15 Years**

(21) Appl. No.: **29/918,475**

(22) Filed: **Nov. 28, 2023**

Related U.S. Application Data

(63) Continuation of application No. 29/876,378, filed on May 19, 2023, now Pat. No. Des. 1,009,020.

CLAIM

The ornamental design for a set of electronic devices, as shown and described.

DESCRIPTION

FIG. 1 is a perspective view of an embodiment of our new design of a set of electronic devices;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

The oblique lines represent a transparent or translucent surface.

The broken lines showing portions of the set of electronic devices form no part of the claimed design.

1 Claim, 7 Drawing Sheets
